RICHARD S. BETTS AND PERRY H. HAMILTON, OF MEMPHIS, TENNESSEE.

RAILWAY-SWITCH.

1,192,737.

Specification of Letters Patent. Patented July 25, 1916.

Application filed December 7, 1914. Serial No. 875,831.

To all whom it may concern:

Be it known that we, RICHARD S. BETTS and PERRY H. HAMILTON, citizens of the United States, and residents of Memphis, 5 in the county of Shelby and State of Tennessee, have made an Improvement in Railway-Switches, of which the following is a specification.

Our invention relates to an improvement 10 in so-called split switches as distinguished from stub switches, the object being to prevent the flanges of car or locomotive wheels from striking and thus wearing and blunting the switch point.

15 The details of construction, arrangement, and operation are as hereinafter described, and illustrated in the accompanying drawing, in which—

Figure 1 is a plan view of a switch including our improvement. Fig. 2 is a side view of same. Figs. 3 and 4 are enlarged vertical cross sections on the lines 6—6 and 7—7, respectively, of Fig. 1.

In Figs. 1 and 2, the numeral 1 indicates 25 the scarfed, shiftable, switch-rail or switch-point, and 2 indicates the fixed stock, or running, rail with which said switch-rail is adapted to co-act in the well known manner.

The lateral guard or protector 8 is provided 30 with a curved top flange 8^b extending above the head of the stock rail 2 and spaced therefrom by a narrow horizontal shelf which is at the same level with the head of the rail. The inner side of the guard 8 35 abuts and thus braces, or affords lateral support for the head of the rail and the screw bolts 4 pass transversely through both the guards and rail, thus securing them firmly together.

The base of the guard 8 extends under the 40 base of the rail 2 and the guard is recessed on the inner side to receive the adjacent base flange of the rail, which latter rests directly on the horizontal laterally extended flange of the guard, as shown in Figs. 3 and 4. 45 The guard has a brace 8^a on the outer side through which the bolts 4 pass.

In use of the switch, the outer sides of car or locomotive wheels abut and run in contact with the vertical flange 8^b so that the flanges 50 of the wheels cannot come in contact with the switch point, this result being due not merely to the contact of the wheel with the flange 8^b, but also to the fact that the tread of the wheels is wider than the combined 55 thickness of the rail head 2 and the adjacent shelf of the guard 8.

What we claim is:—

The combination with a switch point and running rail arranged alongside each other, 60 of a guard and protector for the switch point, the same consisting of a block having a top flange which extends alongside of and above the top of the running rail and thus affords direct lateral support for the latter, 65 and bolts passing through said block and the running rail and securing the two rigidly together, whereby the guard is adapted to deflect train wheels laterally in passing the switch and at the same time serves as a 70 lateral brace for the running rail, as described.

RICHARD S. BETTS.
